UNITED STATES PATENT OFFICE.

BAINBRIDGE W. BURDICK, OF ALBANY, NEW YORK.

DESIGN FOR A SCREW-SHELL.

SPECIFICATION forming part of Design No. 30,780, dated May 16, 1899.

Application filed May 26, 1898. Serial No. 681,748. Term of patent 14 years.

To all whom it may concern:

Be it known that I, BAINBRIDGE W. BURDICK, a citizen of the United States, residing at Albany, in the county of Albany and State of New York, have invented and produced a new and original Design for a Screw-Shell, of which the following is a specification, reference being had to the accompanying drawings, forming a part thereof.

10 Figure 1 is a perspective view of a screw-shell, showing my new design. Fig. 2 is a view of the same from its outer end. Fig. 3 is a section taken in direction of line xx in Fig. 2.

15 As shown in the drawings, the leading and material features of my design consist in a shell having the shape or configuration comprising a spiral-thread-form circular wall A, having extended from one of its ends the ex-

ternal horizontal flange B and having its opposite end terminating with the horizontal internally-extended annular flange C, as shown in the drawings. These flanges B and C are shown to be extended from the spiral-thread-form wall A in reversed directions and in lines 20 transverse to the axis of said wall, the flange B being at what I term the "head" end of the shell and flange C at the "tail" end of the same.

Having described my invention, what I claim as new, and desire to secure by Letters Patent, is—

The design for a screw-shell as herein shown and described.

BAINBRIDGE W. BURDICK.
